D23-331

SR

D7463

DR

D 18,241

DESIGN.

J. B. PIERCE & J. BOND.

RADIATOR.

No. 18,241.

Patented Apr. 3, 1888.

Witnesses.

Henry Ashbury.
Robt. A. Geary.

John B. Pierce
Joseph Bond Inventors.
By James Bangster
Attorney.

UNITED STATES PATENT OFFICE.

JOHN B. PIERCE AND JOSEPH BOND, OF BUFFALO, NEW YORK.

DESIGN FOR A RADIATOR.

SPECIFICATION forming part of Design No. 18,241, dated April 3, 1888.

Application filed January 3, 1888. Serial No. 259,750. Term of patent 7 years.

To all whom it may concern:

Be it known that we, JOHN B. PIERCE and JOSEPH BOND, both citizens of the United States, residing in Buffalo, in the county of Erie and State of New York, have invented and produced a new and original design for Radiators, of which the following is a specification, reference being had to the accompanying photograph, forming a part thereof.

10 The accompanying photograph represents a perspective view of one of our newly-designed radiators.

The radiator sections or loops 1 are each connected together and provided with an imitation of blackberry-leaves, 2, arranged to run from or over the top of each loop or section 1 partly down each side and combined with buds and flowers 3 4. On the lower portions of each 15 loop or section 1, on each side, is a row of similar leaves, 2, and buds and flowers 3 4, projecting a short distance upward from the bottom and leaving a plain smooth space, 5, between the two ornamental portions, as shown in the accompanying photograph, the design giving the radiator the appearance of being 25 trimmed at the top and bottom of each section with parallel rows of leaves, flowers, and buds, the leaves, flowers, and buds at the top pointing from the top downward and those at the bottom pointing upward. 30

We claim as our invention—

The design for a radiator, consisting of vertical sections or loops connected together and ornamented at their upper and lower portions with figures representing blackberry-leaves, 35 combined with buds and flowers, substantially as shown and described.

JOHN B. PIERCE.
JOSEPH BOND.

Witnesses:

JAMES SANGSTER,
HENRY ASHBERY.